DRILL BIT

Martin Hokanson, Duluth, Minn., assignor to
Eideco, Incorporated, Duluth, Minn., a corpora-
tion of Minnesota

Application August 21, 1939, Serial No. 291,168

7 Claims. (Cl. 255—73)

This invention relates to drill bits and has special reference to improvements in that type of bit illustrated in my United States Patent No. 2,147,343, dated Feb. 14, 1939, and in my copending applications, Ser. Numbers 251,830; 264,791 and 284,939, and is indicative of that type of improvements that can only be accomplished by continued and extensive experimentation in actual practice with such a drill.

It has been found that in the larger types of such a drill, increased speed and efficiency are accomplished by the material modifications and improvements shown, described and claimed in the instant case.

The duplication of the reaming action of an intermediate cutting portion of the bit is believed very material in the practical use of the bit in respect to both speed of cutting and straightness of hole. This is particularly true when it is realized that in a large bit of this type, the intermediate reamer protrudes materially beyond the plane of the cutting edge of the outer or major reamer, but, due to its relatively short length, requires no clearance taper whatever which reduces the gage loss to an absolute minimum, and also has the minimum tendency of deviation from a straight hole.

A further advantage of duplication of the major reaming portion is that they differ only in size and are subject to repeated sharpening from the inside of the depression by a like shaped grinding or forming tool.

The principal object of the invention is to divide up the ring formed between the outside reamer and the central cutter by means of one or more sub-reamers. In this way the width of these rings are cut in half or a third, etc., which makes the spalls less in size and more suitable for discharge out of the hole.

Other objects and advantages of the invention will appear in the following description thereof.

Referring now to the accompanying drawings, forming part of this application, and wherein like reference characters indicate like parts:

Figure 1 is a central vertical section, partly in elevation, of a drill bit embodying the invention.

Figure 2 is a similar view taken at right angles to Figure 1.

Figure 3 is a plan view of the cutting face of the bit.

Figure 4 is a view similar to Figure 1 except that the various parts of the drill are shown integral, and the central cutter is of the reamer type.

Figure 5 is a view similar to Figure 4, except that it is at right angles thereto, and the central cutter is illustrated as being removable.

Figure 6 is a view of the cutting face of the bit shown in Figures 4 and 5.

While in the embodiment shown in Figures 1

and 2 the various cooperative parts of the bit are shown as being screw-threaded as by V-shaped threading of the parts, it is thought obvious that in view of the various forms of such union as for example by square threads, or modified friction joints, which may be resorted to and are common in the art, further illustration or reference thereto is unnecessary, or that the parts may be formed integral as shown in Fig. 4, or any one of them separable as shown in Figure 5, without departing from the spirit of the invention.

In all modifications I have illustrated the bit as being provided with a tapered spigot 1 for a suitable friction union to the operating mechanism for imparting reciprocal motion thereto, and this may be either a drill rod or a cable operating means.

The spigot 1 is shown as being formed integral with the cylindrical shank 2 of the bit, which, in this instance, tapers from the lower portion thereof in opposite directions, as at 3, to the upper smaller end of the head portion 4. This head portion is illustrated as comprising two opposed arcuate reaming portions 5 lying in the same circle with the diametrically opposite portions of the head being flattened as illustrated at 6 in planes parallel with the axis and extending upwardly from the corners of the reaming edges to the point indicated at 7, which point is the junction of the inclined surface 3 with such plane surfaces.

The flattening of the sides in this manner is to provide ample clearance for the detritus or spalls, and obviously may be enlarged or reduced as required in respect to the character of the material being drilled. However the proportions here illustrated are deemed ideal in that such ample clearance is provided, and the strength of the bit head is in no wise impaired.

To further insure ample clearance for spalls it is to be noted that the lower edge of the head 4 intermediate of the opposed corners 8—8 in respect to each flattened portion 6 is arched upwardly as at 9 and is cut away on an incline forming the bevel surface 10, and this cut-away portion may be varied materially in respect to the character of work being performed.

In respect to the angle of the walls of the depression which form the reaming edges 5, they are illustrated as being of compound angular form, first of all to give strength to the cutting edge and also for the purpose of lessening the amount of grinding necessary in sharpening the bit, which is always sharpened from the inside concavity by means of suitable grinding wheels.

Within the hollow portion of the head 4 of the bit illustrated in Figures 1 and 2 is installed the secondary or sub-reamer 11, it terminating downwardly in the opposed reaming edges 12 which in practically all respects is similar to the cutting

edges 5 of the outer reamer. However the lower portion of this auxiliary reamer is preferably of cylindrical form except that it is cut-away similar to the outermost reamer, the diametrically opposite edges thereof forming the inclined arcuate surface 13, similar to the surface 10 in the outer reamer, to provide clearance for the spalls of the pilot portion of the bit. It will be noted that the sub-reamer is disposed with the cutting edges in alignment with the cutting edges of the outer reamer to insure freedom of the spalls so that no obstruction exists as the bit rotates during its reciprocal action, though, obviously, in some instances, it may be equally or more efficient to have the medial line through each cutting edge disposed at an angle to each other. The construction of this auxiliary reamer differs but slightly from that of the outer reamer in that although it is constantly forming a hole of shallow depth immediately in advance of the work of the outer reamer, the hole is so shallow that the auxiliary reamer does not need the tapered outer surface clearance angle which is required by the larger outer reamer. This construction of the auxiliary or sub-reamer is of great advantage because it may be ground many times with the absolute minimum loss of gage, and provides added guidance to the drill in keeping it in perfect alignment.

The flattened sides 19 of the sub-reamer, as well as those 18 of the central cutter portion, serve also for the purpose of convenience relative to the unscrewing of these parts from their respective sockets as by a wrench or the like.

While I have illustrated this type of bit as having a plurality of reamers one within another and an axially disposed pilot chisel, the reamers each having two opposed arcuate cutting edges, it is to be understood that the reamers may be constructed with three or more such arcuate cutting edges, as illustrated in my copending application, Serial Number 284,939, without departing from the spirit of the invention.

In Figures 4, 5 and 6 are illustrated certain modifications of the drill bit, such, for example, as in Figure 4, wherein all cutting portions of the bit are shown as being of integral construction and of reamer type, as, in using a reamer, sub-reamer, and a reamer type cutter, it is quite possible that the actual wear of all parts would be quite similar, and, in such a case, it is quite practical to form them in one integral piece and sharpen the bit by means of ring grinders for the reamer portions and a cone or spherical grinder for the cutter portion.

In Figure 5 the leading cutting portion of the bit is illustrated at 20 and is shown as being removable and attached to the head portion of the bit as by a suitable friction joint, common in the art. There are cases when it may be desirable to use a reamer, sub-reamer, which are integrally formed, with a cutter chisel of any of several types, and thus it is illustrated as removable for such cases.

Having thus described my invention, what I claim and desire to secure by Letters Patent, is:

1. A drill bit for percussion rock drilling comprising a body portion having an axial fluid passageway therethrough for access of fluid to the working face of the bit body, said body terminating at one end in a cylindrical shank and means for application to the lower end of a drill rod, the body portion below said shank being hollow, enlarged and depressed at spaced intervals about the periphery of said enlargement, 75

an axial depression in said body portion forming the lower outer portions of said enlargement into a plurality of spaced arcuate reaming edges, a secondary hollow reamer of smaller diameter within the hollow of said head and projecting axially from said enlargement having spaced depressions about its periphery, an axial depression within said secondary reamer terminating at its lower outer edges in a plurality of spaced arcuate cutting edges, and a central axially disposed cutter portion within and projecting axially from and of smaller diameter than said sub-reamer.

2. A drill bit of the type described having an axial fluid passageway therethrough, comprising an outer reaming portion having a plurality of spaced arcuate reaming edges formed by a depression therein, a secondary reaming portion within and projecting from the depression in said outer reamer portion, said secondary reaming portion having a depression therein and a plurality of spaced arcuate reaming edges, and a central cutter portion within and projecting from the depression in said secondary reaming portion.

3. A drill bit substantially as set forth in claim 2 wherein all of the cutting edges of said reaming and central portions are so formed as to break the cuttings therefrom inwardly.

4. A drill bit substantially as set forth in claim 2 wherein the space between each pair of arcuate cutting edges is upwardly arched and beveled to form additional cutting edges.

5. A drill bit of the type described for percussion rock drilling, comprising a substantially cylindrical shank portion, and an integral enlarged head, the lower outer portion of which terminates in a plurality of projecting arcuate reaming members and having a socket axially within said lower head portion, a secondary smaller reaming member removably applied to said socket, the lower outer portion of which terminates in a plurality of circumferentially spaced arcuate reaming edges projecting beyond a plane with said first mentioned reaming edges, said secondary member also having a socket axially of and extending inwardly from the lower outer portion thereof, and a third cutting member removably applied to the socket in said secondary member and extending beyond a plane with the arcuate reaming edges thereof, said sockets and removable members each extending but a portion of the length of the members in which they are formed to insure as sturdy and durable a separable bit as possible.

6. A drill bit for percussion rock drilling comprising a head portion consisting of a plurality of substantially similarly shaped reamers, progressively graduated in size, each consisting of a substantially cylindrical body, flattened at spaced intervals about its sides and having an axial depression in the face and extending to the periphery thereof said depression having an axis coincident with the bit axis and forming the lower outer end into a plurality of spaced arcuate reaming cutting edges lying in the same circle, the largest of said reamers being removably attachable to the lower end of a string of drill rod and each of said smaller reamers extending from the depression in the next larger reamer.

7. A drill bit substantially as set forth in claim 6, characterized by the spaces intermediate of each adjacent pair of arcuate cutting edges being cut-away arcuately on an axis transverse the bit.

MARTIN HOKANSON.
